CHARGE FORMING DEVICE

Fred E. Aseltine, Carl H. Kindl, and William G. Pontis, Dayton, Ohio, assignors, by mesne assignments, to General Motors Corporation, Detroit, Mich., a corporation of Delaware

Application May 4, 1929, Serial No. 360,404

54 Claims. (Cl. 261—41)

This invention relates to charge forming devices for internal combustion engines, most particularly to that type of charge forming device which comprises a plurality of primary carburetors, one for each intake port of the engine, and which cooperate respectively with a plurality of secondary carburetors, each of which is located adjacent an engine intake port and receives a primary mixture of fuel and air from a pipe connected with one of the primary carburetors, while receiving additional air when required, through one branch of an air manifold which supplies air to all of the secondary carburetors. An example of a charge forming device of this character is disclosed in the application of Fred E. Aseltine, Wilford H. Teeter, and Carl H. Kindl, Serial No. 288,683, filed June 27, 1928, which matured into Patent No. 1,937,938, of Dec. 5, 1933. In the device disclosed in the above mentioned application and in other earlier devices of similar nature, a plurality of primary carburetors are provided and the fuel and air mixture is conducted from the primary carburetors through relatively small conduits to secondary carburetors, located adjacent the engine intake ports, where it is mixed with secondary air admitted to the main air manifold through a single port controlled by a spring held valve. Throttling of the engine is effected by a single primary throttle which controls all the primary carburetors and a single main air throttle controlling the flow of air through the air manifold. These throttles are operated from a common operating mechanism so constructed that the primary throttle moves independently of the main throttle up to a predetermined engine speed, for example, that corresponding to a vehicular speed of 20 to 25 miles per hour on a level, after which the two throttles are operated simultaneously. A plurality of means are provided to variably control the admission of fuel and air under different operating conditions to provide a mixture of proper proportions to most satisfactorily operate the engine.

It is the principal object of the present invention to provide a charge forming device of the character above referred to which is simplified in construction, is provided with improved means for controlling the supply of fuel and air by means of which proper proportioning of the mixture may be secured to most satisfactorily operate the engine under all operating conditions, and which may be easily and cheaply manufactured.

With these objects in view, one feature of the present invention resides in the provision of novel

means for supplying fuel to the primary mixing chambers, such means consisting of a plurality of fuel jets, one of which is controlled by a fixed metering plug and the other of which is controlled by a plurality of valves operated in the 5 manner hereinafter described.

A further feature of the invention resides in the provision of improved means for operating the two throttle valves and for controlling the operation of a suction operated auxiliary air valve 10 in the main air passage.

A still further feature of the invention consists of a new and improved pump for supplying accelerating fuel on opening movements of the throttle, operated by the primary throttle 15 through the medium of improved operating mechanism and effective to pump the fuel to a well in which substantially atmospheric pressure is maintained and from which it is supplied to the mixing chambers by the action of gravity. 20

An additional feature of the present invention resides in the provision of a novel form of dash pot for controlling the opening movements of the auxiliary air valve, improved means being provided to render said dash pot substantially ineffective to retard the movement of said air valve under certain predetermined operating conditions. 25

A still further feature of the present invention comprises a suction operated fuel valve in a 30 conduit leading to certain of the fuel jets, said valve being provided with a passage therethrough to permit a limited flow of fuel when the valve is seated and with two exteriorly tapered surfaces 35 which are adapted to variably control the flow of fuel when the valve is lifted from its seat.

A still further feature of the invention consists in the provision of channels in the surface of the air valve which permit a limited amount 40 of air to enter the carburetor when the valve is closed to provide the air necessary for starting.

A still further feature of the invention resides in the provision of means to communicate the manifold suction to the anterior side of the auxiliary air valve, so as to assist in holding said 45 valve closed when the throttles are closed, to delay the opening movement of the valve and to admit air to the primary mixture passages from the main air passage under certain operating 50 conditions.

Another feature of the invention resides in the provision of improved means for straightening and accelerating the flow of air past the delivery ends of the primary mixture conduits and for 55 causing such air to move in straight paths.

Further objects and advantages of the present invention will be apparent from the following description, reference being had to the accompanying drawings wherein a preferred embodiment of one form of the present invention is clearly shown.

5 In the drawings:

Fig. 1 is a plan view of a charge forming device embodying this invention, the manifold being broken away in order to show the end branches thereof.

Fig. 16 is a detail view of the primary throttle.

Fig. 17 is a diagrammatic view showing in one figure the valve operating mechanism and the fuel passages.

40 The device disclosed herein comprises a main air manifold 10, having three outlet branches 11, 12, and 13, each of which is adapted to communicate with one of the intake ports of a multi-cylinder engine in each of which branches is formed 45 one of the secondary mixing chambers to which a primary mixture of fuel and air is admitted in a manner set forth hereinafter. These branches are each provided with an attaching flange 14, which is adapted to be attached to the engine 50 block in the conventional manner. Adjacent its inlet, the manifold is provided with a flange 15, to which the main carburetor unit hereinafter described is adapted to be secured, as shown in Fig. 3.

55 The main carburetor unit comprises a main housing 16 in the form of a single casting having a flange 17 secured by screws 18 to the flange 15. A valve controlled air inlet, coupling 19, is secured in position over an opening in the top of the housing 16 by screws 20, as shown in Fig. 4, or in any other desirable manner. A casting 21 having a pump cylinder and certain dash pot chambers hereinafter described, formed therein, is secured by screws 22 to the bottom of the main 60 housing, a gasket 23 being provided to prevent leakage. A sheet metal fuel bowl forming a main fuel reservoir 24 is held tight against the bottom of the main housing by a screw 25, screwed into the casting 21 and a gasket 26 forms a tight joint 65 between the bowl and the main housing.

70 A fuel supply line leading from a main source of fuel supply communicates with a passage in a projecting boss 30, this passage communicating with an angular passage 31 formed in the bottom wall of the main housing. The passage 31 con-

ncts with a bore 32 in the casting 21, a nipple 33 being screwed into the enlarged lower end of this bore. The passage through the nipple is restricted at 33a to form a valve seat with which the valve 34 cooperates. This valve is of square cross section so as to permit the flow of fuel past the valve when it is off of its seat and is controlled by a float 35 secured to an arm 36, pivoted at 37 and engaging the valve 34 to operate said valve in the usual manner to maintain a constant level of 10 fuel within the fuel chamber 24.

15 A plurality of primary mixture passages indicated in their entirety by the reference character 40, and hereinafter more fully described, are formed in the lower part of the main housing 16. In each of the primary mixture passages are two fuel nozzles 41 and 42, these nozzles being rendered effective successively in a manner to be later described, and constituting low and high speed fuel nozzles respectively. Fuel is conducted from 20 the fuel chamber 24 to the low speed fuel nozzles 41 through a passage 43 and to the high speed fuel nozzles by a separate passage which will be described more fully hereinafter. The passage 43 in the casting 21 extends vertically from the 25 bottom of said casting to a channel 44 formed in the upper surface thereof and extending transversely, as shown in Fig. 10, so as to communicate with all the nozzles 41. The flow of fuel through the passage 43 and to the nozzles 41 is controlled 30 by a calibrated metering plug 45 having a fixed orifice therein and screwed into an enlarged portion of the passage 43 adjacent the lower end thereof. It will be understood that the nozzles 41 are in constant communication through the 35 above described passages with the fuel in the fuel chamber and such nozzles are effective at all operating speeds to supply fuel to the afore-mentioned mixture passages.

40 The high speed fuel nozzles 42 are entirely 40 ineffective during operation at low engine speeds and are rendered effective by means of the valve 46 operated by the throttle in a manner to be later described. The valve 46 is normally held 45 in position to close a fuel supply port 47 in the casting 21, by means of a spring 48 which is received in a bore 49, in which the valve 46 is 50 slidably, between the lower end of the valve and the plate 50 secured to the bottom of the casting 21. The passage 47, the bore 49 and a 55 horizontal passage 51, comprise a fuel passage which communicates with a vertical passage 52, the upper end of which connects with a channel 53 similar in form to the channel 44 and communicating with all of the high speed nozzles 55 42, which project slightly above the floor of the mixture passages 40, as illustrated in Figs. 3 and 11. The flow of fuel through the passages above described to the high speed nozzles 42 is controlled by three elements, the valve 46, 60 above referred to, a calibrated metering plug 54 having a fixed orifice 55 formed therein which controls the maximum flow, and a suction operated metering valve 56 which automatically 65 regulates the flow of fuel to the high speed jets in accordance with the suction effective on the column of fuel flowing through the above described passages to said jets.

70 The valve 56 is received in an enlarged bore 57 forming a part of the passage 52 and fits in 70 said bore loosely enough to permit the passage of fuel around the valve to the high speed jets. The valve is provided with a passage 58 therein which permits a flow of fuel through the valve when the suction effective on said valve is very 75

low and not enough to lift the valve from its normal seated position. The passage 52 is provided with two shoulders 59 and 60 formed on the wall of said passage and adapted to cooperate with two tapered surfaces 61 and 62, on the exterior of the valve, while an external rib 63 is provided at the top of the valve, as indicated in Fig. 9. In its normal position, as shown in such figure, the valve is in its lowermost position with the surfaces 62 engaging the shoulder 60 and the tapered surface 61 spaced slightly from the shoulder 59. Any flow of fuel with the valve in this position must take place through the passage 58 within the valve, but as the throttle valve is opened and the suction communicated to the high speed nozzles is increased in the manner hereinafter described, the valve is lifted so that the passage of fuel around the valve is permitted. The tapered surfaces 61 and 62 are of slightly different angularity so as to exert a variable restriction on the flow of fuel as the valve is lifted. It will be clear from the above that the suction operated valve 56 exerts a variable control on the flow of fuel to the high speed nozzles after the valve 46 has been opened. Moreover while the valve 46 is stationary, any change in load which would vary the engine speed and, therefore, vary the engine suction, is effective to vary the position of the valve 56 to variably regulate the flow of fuel.

Each low speed fuel nozzle 41 is provided with a main fuel outlet 64 in the top of the nozzle and a secondary fuel outlet comprising two small holes 65 and 66 diametrically opposite each other in the vertical wall of the nozzle near the bottom of the primary mixture passages. At very low speeds the suction is sufficient to cause a flow through the orifices 65 and 66 only, but on high speeds the suction is great enough in the primary mixture passages to lift fuel through the main fuel outlets as well as from the orifices 65 and 66. Only one fuel outlet is provided in each high speed nozzle 42. The low speed nozzles are each provided with a restricting metering orifice 67, and the high speed nozzles with a similar metering orifice 68.

The primary mixture passages 40 are enlarged adjacent the fuel nozzles as indicated at 70 and these enlargements constitute the primary mixing chambers. These chambers all communicate with a single chamber 71, which for convenience may be termed a primary air chamber and which communicates with a main air chamber in a manner to be described hereinafter. There are three of the primary mixture passages 40 which are parallel to each other and relatively close together, as indicated in Fig. 4. These passages communicate with passages 72 formed in the wall of the manifold and which may be termed for convenience primary mixture conduits. The middle passage 72 is straight and receives a tube 73, which conveys primary mixture to the secondary mixing chamber associated with the middle branch 12 of the manifold. The other two passages 72 are substantially L-shaped and connect with pipes 74 which communicate with tubes 75 and 76 in the manifold branches 11 and 13 respectively, and which are of substantially the same construction as the tube 73. The pipes 74 communicate with elbows 76 which are screwed to bosses 77 on the manifold and in turn communicate with the tubes 75 and 76, as indicated in Fig. 1. The primary mixture passages are all considerably restricted at the outlet of the primary mixing chambers 70, as indicated at

78 for the purpose of materially reducing the velocity of flow through the mixing chambers adjacent the nozzles for a purpose which is fully set forth in the above-mentioned application and need not be repeated herein.

A single throttle valve 80 is rotatably mounted in the main housing 16 and controls all of the mixture passages 40, this valve being provided with grooves 82 which register with the said mixture passages and with spindles 84, which project from each end thereof outside the housing so that certain valve operating devices hereinafter described may be secured thereto. This throttle controls the flow of primary mixture from the primary mixing chambers through the pipe connections described in the preceding paragraph, to secondary mixing chambers where such mixture is adapted to be mixed with additional air under certain operating conditions in the manner later described.

Substantially all of the air supplied to both primary and secondary mixing chambers is admitted through the coupling 19 to a main air chamber from which the air flows to both the primary and secondary mixing chambers. The flow of air is controlled by means of a valve 85 normally held against its seat 86 by a spring 87 which is received between the valve and the flange 88 projecting from a sleeve 89, which is slidably mounted on a sleeve 90, fixed in position in the main housing 16. Under normal operating conditions the sleeve 89 is in the position shown in Fig. 3, but may be lifted from this position by means of choke mechanism hereinafter described, to hold the air valve 85 closed to facilitate start-

ing. The choke mechanism comprises a lever 91 pivoted on a screw 92, screwed into bosses 93 and 94, formed on the main housing, as indicated in Fig. 5. A suitable operating connection is adapted to extend from the upper end of lever 91 to some position convenient to the operator, while an adjustable stop screw 95 is adapted to engage the main housing and may be adjusted to different positions so as to variably determine the normal position of the lever 91, and in this manner regulate the normal tension of the spring 87. The lever 91 extends through the wall of the main housing and is provided with a toe 96, which extends beneath the flange 88 to lift the flange 50 when the lever 91 is rocked in a clockwise direction in Fig. 4, to engage the upper end of the sleeve 89 with the valve 85 to hold the latter closed. When the air valve is held closed in this manner, sufficient air to carry the starting fuel 55 from the primary mixing chambers to the engine ports is admitted through the air channels 97 formed in the upper surface of the air valve 85.

The valve 85 controls the admission of air to a main air chamber 100 formed in the housing 16 and communicating with the primary air chamber 71 by means of a relatively large orifice 101 in the floor of said main air chamber. Air also flows from said main air chamber to the secondary mixing chambers through an air conduit 102, which may be termed a secondary air passage and is controlled in a manner hereinafter described, by the manually operable valve 103, secured to the shaft 104, pivoted in the main housing and a suction operated valve 105 secured to a shaft 70 106, also pivoted in the main housing. The operating mechanism for these valves will be described in detail hereinafter. In addition to the air supplied to the primary mixture passages through the orifice 101, air is also supplied to these pas-

sages from the main air chamber 100 through three passages 107, which communicate with the primary mixture passages immediately posterior to the restriction 77 hereinbefore referred to. 5 These passages serve to admit air to the primary mixture passages for the purposes of reducing the velocity of flow past the fuel jets for a purpose substantially the same as in earlier devices of this character and which is fully explained in the 10 above mentioned application Serial No. 288,683.

During operation at all engine speeds below a certain predetermined speed, such for instance as 20-25 miles per hour on a level, the mixture formed in the primary mixing chambers is of 15 properly combustible proportions and this mixture may be conveyed to the engine without dilution by admixture with the additional air in the secondary carburetors. At all higher engine speeds the primary mixture becomes super-rich 20 in fuel content due primarily to the presence of a velocity head at the nozzles at such speeds. To off-set the too rapid increase in fuel flow and to provide a mixture of properly combustible 25 proportions, the air passage 102 leading from the main air chamber 100 to the air manifold must be opened in order to admit air to the secondary mixing chambers to dilute the primary mixture which is delivered thereto.

The mechanism for operating the valves 103 and 105 will now be described. The valve 103 is operated by means of the primary throttle after the primary throttle has made a certain amount of independent movement, subsequent to which movement the valve 103 is moved with said primary throttle. To this end a throttle operating cam 110 is secured to the spindle 84 projecting from the right end of the primary throttle shaft as viewed in Fig. 1. This cam is provided with an orifice 111 in which any suitable form of operating connection may be secured. Adjustably secured in an arm 112 projecting from the cam, is a stop screw 113, which is adapted to engage an arm 116, hereinafter more fully described, to determine the position of the cam and the primary throttle when the engine is stopped or idling. By adjusting the screw 113, the area of the primary mixture passages, when the throttle is closed, may be adjusted and the idling speed of the engine in this manner determined. An operating slot 114, a portion of which is concentric with the spindle 84, is formed in said cam 110 and engages a pin 115 projecting from an arm 116, adjustably secured in any desirable manner to the end of the shaft 104 on which the secondary air throttle 103 is secured. In the normal position of the parts, as shown in Fig. 5, the pin 115 occupies a position adjacent one end of the slot 114 in that part of the slot which is concentric with the spindle 84. The slot is so designed 60 that the cam 110 may make some degree of movement before the pin 115 reaches that portion of the slot which is not concentric with the spindle, whereby a certain amount of independent movement of the primary throttle is effected without 65 any corresponding movement of the secondary throttle. After the cam has been moved to a position where the pin 115 is in a portion of the slot 114 which is not concentric with the spindle, the valve 103 is moved simultaneously with the 70 primary throttle and the degree of movement of such valve is dependent upon the contour of the cam slot 114, which may be made of any desired shape to give the desired amount of movement to the valve 103. It will be obvious that by substitution of a cam having a slot 114 of different

contour, the degree of movement imparted to the valve 103 may be changed as desired.

As indicated above, the stop screw 113 is adapted to engage the arm 116 to determine the closed position of the primary throttle. With the parts in normal position, the air valve 103 is fully closed and when the cam is moved in a clockwise direction to move the primary throttle toward its closed position, it may continue to move until the screw 113 engages the arm 116, which is held stationary when the valve 103 reaches its closed position and thus prevents further closing movement of the primary throttle.

The valve 105 is adapted to be opened entirely by the suction of the engine, but said valve is 15 adapted to be closed by the throttle operating mechanism through the medium of a spring hereinafter described. For this purpose an arm 117 is adjustably secured to the shaft 104 in any desirable manner, and is connected by means of 20 link 118 with an arm 119 secured on the shaft 106 on which the valve 105 is fixed. The link 118 is connected to the arms 117 and 119 by pins 120 and 121 respectively, which project through slots 122 and 123 formed in the link 118. The link is 25 connected to the arm 117 by means of a spring 124, which tends to pull the link toward the left in Fig. 5, so that the pin 121 occupies the position in slot 123 illustrated in that figure. On operation of the cam 110 to close the primary throttle, the 30 link 118 is moved toward the left in Fig. 5 by the spring 124, which is stretched by the clockwise movement of arm 117, so as to rock the arm 119 in a clockwise direction and close the valve 105, the parts assuming the position shown in Fig. 5 35 at the end of the closing movement. When the cam 110 is moved in a counterclockwise direction on opening of the primary throttle, the arm 117 is also moved in a counterclockwise direction and the link 118 is moved to the right as shown in Fig. 40 5 without effecting any movement of the valve 105 because of the provision of slot 123, the pin 121 merely moving in said slot during such movement of the link 118. After the valve 103 begins to open, the suction effective on the valve 105 will open 45 said valve and swing the arm 119 in a counterclockwise direction, the movement of said valve being limited by the engagement of the pin 121 with the end of slot 123.

It will be noted that three orifices 125 are provided which connect the space in the passage 102 between the valves 103 and 105 with the three primary mixture passages 40. These orifices communicate the suction of the primary mixture passages to the space between the valves 103 and 105 55 tending to hold the valve 105 closed when the throttle 103 is closed and until the pressure differential on opposite sides of the valve 105 is enough to overcome the resistance of a dash pot normally retarding the opening movement of said valve 105. 60 These orifices therefore effect a slight delay in the opening of valve 105 from its closed position, with respect to opening of the air throttle 103.

On opening movement of either or both of the throttle valves, the suction in the main air chamber 100 is increased and the air valve 85 is opened against the tension of its spring permitting an increasing flow of air past said valve. During opening movements of said valve it has been found that the valve will flutter unless means are 65 provided to prevent such action. In order to produce a steady opening movement of the valve, a dash pot of conventional form is provided comprising a cylinder 130 formed in the casting 21 and a cooperating piston 131 secured to the lower 75

end of the air valve stem. This dash pot is of well known construction and is adapted to be filled by leakage around the piston when the valve is stationary, fuel escaping slowly from the cylinder by leakage around the piston during opening of the air valve, whereby the movement of the valve is steady.

On opening movements of the throttle valves it is necessary to provide a somewhat enriched mixture in order to properly operate the engine during the acceleration period. For this purpose the device disclosed herein is provided with a pump operated by the primary throttle and hereinafter more fully described to temporarily supply an additional amount of fuel to the primary mixture passages. It has been found necessary, in order to secure the desired mixture enrichment, to also provide means for retarding the opening of the suction operated valve 105 during opening movements of the main air throttle 103. This is necessary in order to produce a sufficient pressure differential between the inlet and outlet ends of the primary mixture conduits to create a velocity of flow through these tubes great enough to transport the enriched primary mixture from the primary mixing chambers to the secondary mixing chambers almost instantaneously. It is a considerable distance from the point at which the fuel enters the primary mixture passages to the secondary mixing chambers where the primary mixture is mixed with air flowing past the air throttle 103 and if the air valve 105 were allowed to open freely, an appreciable time interval would be necessary for the rich and relatively heavy primary mixture to travel through this distance, obviously a greater time interval than that required for the pure air to travel from the air throttle 103 to said secondary mixing chambers. By retarding the opening of the valve 105 the time interval necessary for the primary mixture to reach said secondary mixing chamber is reduced, while that necessary for the air flowing past valve 103 is increased so that these two time intervals approach each other, in fact, are substantially equalized, whereby the enriched primary mixture and secondary air reach the secondary mixing chambers at substantially the same time.

In order to retard the opening movement of the valve 105, the shaft 106 on which said valve is secured has attached thereto outside the housing 16 an arm 135, which is pivotally connected with a link 136, the latter being pivotally connected to one end of a lever 137 pivoted on a pin 138, screwed into the main housing. The lever 137 is pivotally connected at its opposite end to a rod 139 connected at its lower end to a dash pot piston 140 slidably mounted in a cylinder 141, formed in the casting 21, as indicated in Fig. 8. The piston 140 has a slidable fit within the cylinder 141 and sufficient clearance to provide for leakage of fuel past the piston to fill the cylinder when the piston is in its uppermost position. Any opening movement of the valve 105 through the mechanism above described causes a downward movement of the piston 140, which retards the opening of said valve 105 to an extent determined by the amount of clearance between the piston and the cylinder wall.

In order to variably control the resistance of the above described dash pot to opening movements of the valve 105, a by-pass passage indicated in its entirety by the reference character 142, is provided in the wall of the cylinder 141 to permit escape of fuel from below the piston. A valve 143, projecting through the top of the

float chamber, so that it may be operated manually, is provided to regulate the area of the passage 142, and it will be observed that by varying the position of the valve, the area of the passage 142 may be correspondingly varied and the resistance of the dash pot regulated as desired.

It has been found desirable under certain operating conditions when the suction effective on the air valve is very suddenly and very greatly increased to permit the valve 105 to open freely. As an example of operating conditions when this action of the valve is desirable, it may be assumed that the vehicle is coasting down hill at a relatively high speed with the throttles closed and the clutch engaged. At such times the engine is running at relatively high speed and if a grade is reached and the throttle is opened, it is not desirable to retard the opening of the air valve because the engine is already running at speed and no enrichment of the mixture is necessary, but at such times sufficient air must be admitted to the secondary mixing chambers to provide the necessary volume of charge to give the required power. In order to permit the valve 105 to open freely under the conditions referred to, the dash pot cylinder 141 is formed in the casting 21 adjacent an auxiliary cylinder 144 and communicates with said auxiliary cylinder by means of a passage 145, as shown in Figs. 7 and 8. The cylinder 144 is closed at the top except for a relatively small passage 146 and slidably mounted within the cylinder 144 is a piston 147, the upper end of which is solid and is normally held in engagement with a circular rib 148 on the inner surface of the cylinder 144 surrounding the orifice 146 by means of a spring 149 received between the said closed end of the piston and the plate 50 secured to the bottom of the casting 21 in any desirable manner. The piston 147 normally acts as a valve closing the passage 146 and on opening movements of the valve 105, the dash pot piston 140 creates a vacuum within the auxiliary cylinder 144 below the piston tending to pull the piston away from the rib 148. This vacuum is, under all operating conditions except such conditions as above described, insufficient to overcome the force of the spring 149 so that the dash pot is normally effective to retard the movement of the valve. However, when the throttles are opened under operating conditions such as above described, the suction which is immediately effective on the valve 105 tending to open same, is sufficient to overcome the force of the spring 149 and the piston 147 is lifted from the rib 148. The atmospheric pressure of the fuel chamber, therefore, becomes immediately effective over the whole area of the piston head instead of over only the small portion of such head which is directly opposite the orifice 146, and the resistance of the dash pot immediately is correspondingly reduced so that the valve 105 may open substantially freely after the piston has been pulled away from the rib 148. As soon as the suction effective on the valve 105 becomes insufficient to overcome the action of the spring 149, the piston resumes its position against the rib 148 and the dash pot operates as previously described. Projecting into the cylinder 144 beneath the piston 147 is a pin 150 which limits the downward motion of said piston, the pin being secured in the plate 50 above referred to.

According to the present invention, the pump for supplying additional fuel to the primary mixture passages, as alluded to above, is operated by the primary throttle during its opening move-

ment. For this purpose a cam 155 is secured to the spindle 84 and may be formed integral with the cam 116 or secured to said spindle in any other desirable manner. This cam engages a cam 5 follower 156 rotatably mounted on one end of a lever 157 which is provided intermediate its ends, and pin 158 screwed into the main housing. Pivotally connected to the other end of the lever is a piston rod 159 which extends through the top 10 of the float chamber through a hole 160 of sufficient size to permit lateral movement of the rod and a washer 161 may be provided to prevent leakage through the hole. The lower end of the rod is pivotally connected to a pump piston 15 ton 159a which is slidable in a pump cylinder 162 formed in the casting 21. The cylinder 162 is connected to a vertical passage 163 bored in the casting 21, by means of a short horizontal passage 164. The passage 163 is enlarged at its upper 15 end as indicated at 164a and received therein is a check valve 165, which is normally seated on the shoulder 166, formed at the junction of the passage 163 and the enlargement 164a, a pin 167 being provided to limit the upward movement of the check valve. Communicating with the enlargement 164a is a passage 168 which connects with a well 169 formed immediately below a channel 174 of corresponding shape which is formed in the bottom wall of the main housing 16. 20 Communicating with the well 169 are three horizontal passages 171, the opposite ends of which are open to the atmosphere within the float chamber and above the fuel level therein, while intermediate the ends of these passages they 25 communicate with the vertical passages 172 drilled in the casting 21 and communicating at their upper ends with corresponding vertical passages 173 in the bottom wall of the main housing which have restrictions 170 at the top adjacent 30 the connection of such passages with the primary mixing chambers. On operation of the pump piston 159a fuel is forced through the passages 163 and 168 into the well 169 from which it flows through the passages 171 to the vertical 35 passages which communicate with the primary mixing chambers. At the same time air enters the opposite ends of passages 171 and is mixed with the fuel which is carried through the passages 172 to the mixing chamber. Surplus fuel 40 not carried into the mixing chambers as described, runs out of the passages 171 back into the main fuel chamber 24. The check valve 165 prevents a downward flow of fuel through the passage 163 and normally maintains a supply of fuel adjacent the well so that said fuel is forced 45 into the well substantially simultaneously with any movement of the throttle. Air is admitted through the passages 171 so that the suction effective on the well 169 and passages supplying fuel thereto is never sufficient to draw fuel from the pump cylinder, the enriching fuel being supplied only by the action of the pump piston when the throttle is open.

In addition to the above described pump for 50 enriching the mixture another means is provided for supplying additional fuel at all engine speeds above that at which the air throttle 103 begins to open. This additional fuel supply means is made necessary by the rapid reduction in the 55 velocity head at the fuel nozzles which is caused by the opening of the air throttle 103. The fuel metering means is calibrated too small to be theoretically correct in order to compensate for the velocity head, which is present at the fuel nozzles during the operation of the engine at low

speeds, therefore, the fuel nozzles do not supply sufficient fuel to form a rich enough mixture for most satisfactory engine operation after the valve 103 begins to open and some means for supplying additional fuel under such conditions must be provided. In order to supply this additional fuel the port 47 controlled by the valve 46 hereinbefore 5 previously described, is provided. The port is normally closed and throttle operated means are provided to open said valve 46 when the valve 10 103 begins to open. This means comprises a cam 175 secured in any desirable manner to the spindle 83 projecting from the left end of the primary throttle as viewed in Fig. 1. This cam is adapted to engage a roller 176 rotatably mounted 15 on one end of the bell crank lever 177, which is pivoted on a pin 178 screwed into the main housing. The other end of the lever 177 is provided with a bent-over toe 179 which lies above the stem of the valve 46 and in which is threaded an 20 operating screw 180, which is adapted to engage the stem of the valve 46 and which may be locked in position by a lock nut 181. The cam 175 may be of any desirable contour to move the valve at any rate of speed desired and the screw 180 may be locked in position to engage the stem of the valve 46 at any desired point during movement 25 of the throttle.

According to the present invention the secondary mixing chambers have been modified to eliminate as much as possible the restriction of the outlet branches of the manifold, which was effected by the Venturi tubes used therein in earlier forms of this device such as that disclosed in the above mentioned application Serial No. 288,683. 30 In the device herein described, the ends of the primary mixture conduits are surrounded by a fitting comprising an inner tube 185 which is spaced from the primary mixture conduit and is secured by a spider 186 to an outer tube 187 provided with an enlargement 188 forming a shoulder 189, where it joins with the smaller portion 187. When the device is assembled, this shoulder 189 is adapted to be held against a corresponding shoulder 190, formed in the outlet branch of the 45 manifold and the other end of the enlarged portion 188 is adapted to engage a similar shoulder in the engine block. The primary mixture conduit terminates about midway of the length of the inner tube 185 so that the air flowing past the end of said primary mixture conduit is moving in a substantially straight path and since the air flows both within and outside of the tube 185, the fitting restricts the outlet passage very little, the restriction consisting primarily of the 50 ends of the two tubes which are made of relatively thin sheet metal and the arms of the spider which secure the tubes together. The function of the above described structure is substantially the same as that of the Venturi tube heretofore employed, that is to increase the velocity of the air passing the end of the primary mixture conduit and to cause this air to move 55 in a substantially straight path.

While the form of embodiment of the present 60 invention as herein disclosed, constitutes a preferred form, it is to be understood that other forms might be adopted, all coming within the scope of the claims which follow.

What is claimed is as follows:

1. A charge forming device for internal combustion engines comprising a mixing chamber, a fuel reservoir, an air inlet for said mixing chamber, a plurality of fuel inlets discharging fuel into the mixing chamber, separate conduits connect- 75

- ing said inlets respectively with the fuel reservoir for supplying fuel to the fuel inlets, and manually and automatically operable valve means for variably controlling the flow through one of 5 said conduits.
2. A charge forming device for internal combustion engines comprising a mixing chamber, an air inlet therefor, a plurality of fuel inlets discharging fuel into the mixing chamber, a fuel 10 reservoir for supplying fuel thereto, a throttle, means operated by the throttle for rendering one of said fuel inlets effective and additional means for regulating the flow through said fuel inlet.
3. A charge forming device for internal combustion engines comprising a mixing chamber, an air inlet therefor, a plurality of fuel inlets discharging fuel into the mixing chamber, a fuel 15 reservoir for supplying fuel thereto, valve means for rendering one of said fuel inlets effective at higher engine speeds and additional valve means for automatically and variably regulating the 20 flow of fuel through said inlet.
4. A charge forming device for internal combustion engines comprising a mixing chamber, fuel and air inlets therefor, a fuel reservoir, a fuel 25 supply conduit connecting the fuel inlet and reservoir, a valve controlling the flow of fuel through said conduit having a passage there- 30 through and a plurality of external flow controlling surfaces and a plurality of restrictions in said conduit adapted to cooperate with said flow controlling surfaces.
5. A charge forming device for internal combustion engines having a plurality of intake ports comprising an individual primary carburetor for 35 supplying fuel mixture to each intake port, a fuel reservoir, a fuel duct for conveying fuel from said reservoir to all of said primary carburetors, a fuel valve for controlling the flow of fuel through 40 said duct having a plurality of external flow controlling surfaces, and a plurality of shoulders in said duct cooperating with said surfaces.
6. A charge forming device for internal combustion engines comprising a mixing chamber, means for supplying fuel and air thereto, a 45 throttle controlling the flow of mixture therefrom, an operating shaft for the throttle, a passage supplying additional air, a valve in said passage and a cam operated by said throttle for 50 operating said air valve, said cam being so designed that the throttle may make a predetermined movement independently of the air valve.
7. A charge forming device for internal combustion engines comprising a secondary mixing 55 chamber, a primary carburetor adapted to deliver a primary mixture of fuel and air thereto, means for supplying fuel and air to the primary carburetor, a primary throttle controlling the flow therefrom, a secondary air passage adapted to 60 supply air to the secondary mixing chamber, a secondary air throttle therein and means for operating said throttles concomitantly, said means including a cam operated by the primary 65 throttle and so designed as to permit a predetermined independent movement of said primary throttle.
8. A charge forming device for internal combustion engines comprising a secondary mixing chamber, a primary carburetor adapted to deliver 70 a primary mixture of fuel and air thereto, means for supplying fuel and air to the primary carburetor, a primary throttle controlling the flow therefrom, a secondary air passage adapted to supply air to the secondary mixing chamber, a 75 secondary air throttle therein, an auxiliary valve in said secondary air passage adapted to be opened as the engine speed increases, a cam operated by the primary throttle for operating said secondary throttle and means controlled by said cam for closing said auxiliary air valve.
9. A charge forming device for internal combustion engines comprising a secondary mixing chamber, a primary carburetor adapted to deliver a primary mixture of fuel and air thereto, means for supplying fuel and air to the primary carburetor, a primary throttle controlling the flow therefrom, a secondary air passage adapted to supply air to the secondary mixing chamber, a secondary air throttle therein, an automatic auxiliary valve in said secondary air passage, a 10 pump for supplying additional fuel during the acceleration period, means for operating said throttles and the pump concomitantly, and means operated by said operating means for controlling the closing of said auxiliary valve.
10. A charge forming device for internal combustion engines comprising a mixing chamber, an air inlet therefor, a plurality of fuel inlets discharging fuel into said mixing chamber, a fuel 15 reservoir, a throttle, separate fuel conduits leading to said fuel inlets, means operated by the throttle for variably controlling the flow of fuel through one of said conduits, and suction operated means for also variably controlling the 20 flow of fuel through said last mentioned conduit.
11. A charge forming device for internal combustion engines comprising a mixing chamber, means for supplying fuel and air thereto, a throttle controlling the flow of mixture therefrom, a passage supplying auxiliary air, a valve in said 25 auxiliary air passage, a cam operated by said throttle for operating said auxiliary air valve, a second suction operated valve in said auxiliary air passage and means operated by the cam for controlling the operation of said suction operated 30 valve.
12. A charge forming device for internal combustion engines comprising a mixing chamber, means for supplying fuel and air thereto, a throttle controlling the flow of mixture therefrom, a passage supplying auxiliary air, a valve in said auxiliary air passage, a cam operated by said 35 throttle for operating said auxiliary air valve, a second suction operated valve in said auxiliary air passage, means operated by the cam for controlling the operation of said suction operated valve and a fuel pump also operated by said cam for 40 supplying additional fuel during the acceleration period.
13. A charge forming device for internal combustion engines comprising a mixing chamber, a fuel reservoir, an air inlet admitting air to said mixing chamber, a plurality of fuel inlets discharging fuel into said mixing chamber, separate 45 conduits connecting said inlets with the fuel reservoir, manual and automatic means for controlling the flow of fuel through one of said conduits, said automatic means comprising a valve operable in accordance with the suction effective 50 on the fuel column in the conduit having the automatic flow controlling means therein.
14. A charge forming device for internal combustion engines comprising a mixing chamber, a fuel reservoir, an air inlet admitting air to said mixing chamber, a plurality of fuel inlets discharging fuel into said mixing chamber, separate 55 conduits connecting said inlets with the fuel reservoir, means for rendering said fuel conduits successively operative whereby one of said fuel inlets may be effective independently of another 60

and additional means for variably controlling the flow through one of said conduits after said conduits become operative.

15. A charge forming device for internal combustion engines comprising a mixing chamber, a fuel reservoir, an air inlet admitting air to said mixing chamber, a plurality of fuel inlets discharging fuel into said mixing chamber, separate conduits connecting said inlets with the fuel reservoir, a throttle, means operated by the throttle when said throttle reaches a predetermined position for rendering one of said fuel conduits effective to supply fuel to the fuel inlet communicating therewith and additional means for regulating the flow of fuel through said last named conduit.

16. A charge forming device for internal combustion engines comprising a mixing chamber, a fuel reservoir, an air inlet admitting air to said mixing chamber, a plurality of fuel inlets discharging fuel into said mixing chamber, separate conduits connecting said inlets with the fuel reservoir, a throttle, means operated by the throttle when said throttle reaches a predetermined position for rendering one of said fuel conduits effective to supply fuel to the fuel inlet communicating therewith, and additional means operable independently of the throttle for variably regulating the flow of fuel through said last named conduit.

17. A charge forming device for internal combustion engines comprising a mixing chamber, a fuel reservoir, an air inlet admitting air to said mixing chamber, a plurality of fuel inlets discharging fuel into said mixing chamber, separate conduits connecting said inlets with the fuel reservoir, a throttle, means operated by the throttle when said throttle reaches a predetermined position for rendering one of said fuel conduits effective to supply fuel to the fuel inlet communicating therewith, and an automatic suction operated valve for variably regulating the flow of fuel through said last named conduit.

18. A charge forming device for internal combustion engines comprising a secondary mixing chamber, a primary carburetor for supplying a primary mixture of fuel and air to said secondary mixing chamber, a primary throttle for controlling the flow of fuel mixture from said primary carburetor, a fuel reservoir, a plurality of fuel inlets discharging fuel into said primary carburetor, separate fuel conduits, each of which supplies fuel to one of said fuel inlets, means operated by the primary throttle for controlling the flow of fuel through one of said conduits and additional means for also regulating the flow of fuel through said last named conduit.

19. A charge forming device for internal combustion engines comprising a secondary mixing chamber, a primary carburetor for supplying a primary mixture of fuel and air to said secondary mixing chamber, a primary throttle for controlling the flow of fuel mixture from said primary carburetor, a fuel reservoir, a plurality of fuel inlets discharging fuel into said primary carburetor, separate fuel conduits, each of which supplies fuel to one of said fuel inlets, means operated by the primary throttle for controlling the flow of fuel through one of said conduits, and automatically operable means for regulating the rate of fuel flow through said last named conduit.

20. A charge forming device for internal combustion engines comprising a secondary mixing chamber, a primary carburetor for supplying a primary mixture of fuel and air to said secondary

mixing chamber, a primary throttle for controlling the flow of fuel mixture from said primary carburetor, a fuel reservoir, a plurality of fuel inlets discharging fuel into said primary carburetor, separate fuel conduits, each of which supplies fuel to one of said fuel inlets, means operated by the primary throttle to render one of said fuel conduits operative to supply fuel to its associated inlet, and means independent of the throttle for regulating the flow of fuel through said last named conduit.

21. A charge forming device for internal combustion engines comprising a secondary mixing chamber, a primary carburetor for supplying a primary mixture of fuel and air to said secondary mixing chamber, a primary throttle for controlling the flow of fuel mixture from said primary carburetor, a fuel reservoir, a plurality of fuel inlets discharging fuel into said primary carburetor, separate fuel conduits, each of which supplies fuel to one of said fuel inlets, means operated by the primary throttle to render one of said fuel conduits operative to supply fuel to its associated inlet, and suction operated means for variably regulating the flow of fuel through said last named conduit as the engine suction varies under different operating conditions.

22. A charge forming device for internal combustion engines comprising a plurality of secondary mixing chambers, a plurality of primary carburetors for supplying a primary mixture of fuel and air to said secondary mixing chambers, a fuel reservoir, means for admitting air to said primary carburetors, low and high speed fuel inlets discharging fuel into the mixing chamber of each primary carburetor, a fuel conduit connecting all of said low speed fuel inlets with said fuel reservoir and a separate and independent fuel conduit connecting all of the high speed fuel inlets with said reservoir.

23. A charge forming device for internal combustion engines comprising a plurality of secondary mixing chambers, a plurality of primary carburetors for supplying a primary mixture of fuel and air to said secondary mixing chambers, a fuel reservoir, means for admitting air to said primary carburetors, low and high speed fuel inlets discharging fuel into the mixing chamber of each primary carburetor, a fuel conduit connecting all of said low speed fuel inlets with said fuel reservoir, a separate and independent fuel conduit connecting all of the high speed fuel conduits with said reservoir, manual and automatic means to variably regulate the flow of fuel through said last named conduit to meet the needs of the engine under varying operating conditions.

24. A charge forming device for internal combustion engines comprising a plurality of secondary mixing chambers, a plurality of primary carburetors for supplying a primary mixture of fuel and air to said secondary mixing chambers, a fuel reservoir, means for admitting air to said primary carburetors, low and high speed fuel inlets discharging fuel into the mixing chamber of each primary carburetor, a fuel conduit connecting all of said low speed fuel inlets with said fuel reservoir, a separate and independent fuel conduit connecting all of the high speed fuel conduits with said reservoir, manual and automatic means to variably regulate the flow of fuel through said last named conduit, said automatic means comprising a suction operated valve subject to engine suction.

25. A charge forming device for internal com-

- bustion engines comprising a plurality of secondary mixing chambers, a plurality of primary carburetors for supplying a primary mixture of fuel and air to said secondary mixing chambers, a fuel 5 reservoir, means for admitting air to said primary carburetors, low and high speed fuel inlets discharging fuel into the mixing chamber of each primary carburetor, a fuel conduit connecting all of said low speed fuel inlets with said fuel reservoir, a separate and independent fuel conduit connecting all of the high speed fuel conduits with said reservoir, and a suction operated valve regulating the flow of fuel through the conduit which supplies fuel to the high speed fuel inlets.
- 10 26. A charge forming device for internal combustion engines comprising a plurality of secondary mixing chambers, a plurality of primary carburetors for supplying a primary mixture of fuel and air to said secondary mixing chambers, a fuel reservoir, means for admitting air to said primary carburetors, low and high speed fuel inlets discharging fuel into the mixing chamber of each primary carburetor, a fuel conduit connecting all of said low speed fuel inlets with said fuel reservoir, a separate and independent fuel conduit connecting all of the high speed fuel conduits with said reservoir, a primary throttle controlling the flow of fuel mixture from the primary carburetors, means operated by said throttle for rendering operative the conduit supplying fuel to the high speed fuel inlets, and other means for regulating the flow of fuel through said last named conduit. 20
- 15 27. A charge forming device for internal combustion engines comprising a plurality of secondary mixing chambers, a plurality of primary carburetors for supplying a primary mixture of fuel and air to said secondary mixing chambers, a fuel reservoir, means for admitting air to said primary carburetors, low and high speed fuel inlets discharging fuel into the mixing chamber of each primary carburetor, a fuel conduit connecting all of said low speed fuel inlets with said fuel reservoir, a separate and independent fuel conduit connecting all of the high speed fuel conduits with said reservoir, a primary throttle controlling the flow of fuel mixture from the primary carburetors, means operated by said throttle after a predetermined opening movement thereof to render the conduit for supplying fuel to the high speed fuel inlets operative, and other means for variably regulating the flow of fuel through said last named conduit. 30
- 20 28. A charge forming device for internal combustion engines comprising a plurality of secondary mixing chambers, a plurality of primary carburetors for supplying a primary mixture of fuel and air to said secondary mixing chambers, a fuel reservoir, means for admitting air to said primary carburetors, low and high speed fuel inlets discharging fuel into the mixing chamber of each primary carburetor, a fuel conduit connecting all of said low speed fuel inlets with said fuel reservoir, a separate and independent fuel conduit connecting all of the high speed fuel conduits with said reservoir, a manually operable valve for rendering operative the conduit for supplying fuel to the high speed fuel inlets, and a suction operated valve for variably regulating the flow of fuel through said last named conduit. 35
- 25 29. A charge forming device for internal combustion engines comprising a mixing chamber, fuel and air inlets therefor, a fuel reservoir, a fuel supply conduit connecting the fuel inlet and reservoir, a valve controlling the flow of fuel 40 through said conduit having a plurality of external flow controlling surfaces thereon, and a plurality of
- 50 51. A charge forming device for internal combustion engines comprising a mixing chamber, fuel and air inlets therefor, a fuel reservoir, a fuel supply conduit connecting the fuel inlet and reservoir, a valve controlling the flow of fuel through said conduit having a plurality of external flow controlling surfaces thereon, and a plurality of
- 55 56. A charge forming device for internal combustion engines comprising a mixing chamber, fuel and air inlets therefor, a fuel reservoir, a fuel supply conduit connecting the fuel inlet and reservoir, a valve controlling the flow of fuel through said conduit having a plurality of external flow controlling surfaces thereon, and a plurality of
- 60 61. A charge forming device for internal combustion engines comprising a mixing chamber, fuel and air inlets therefor, a fuel reservoir, a fuel supply conduit connecting the fuel inlet and reservoir, a valve controlling the flow of fuel through said conduit having a plurality of external flow controlling surfaces thereon, and a plurality of
- 65 66. A charge forming device for internal combustion engines comprising a mixing chamber, fuel and air inlets therefor, a fuel reservoir, a fuel supply conduit connecting the fuel inlet and reservoir, a valve controlling the flow of fuel through said conduit having a plurality of external flow controlling surfaces thereon, and a plurality of
- 70 71. A charge forming device for internal combustion engines comprising a mixing chamber, fuel and air inlets therefor, a fuel reservoir, a fuel supply conduit connecting the fuel inlet and reservoir, a valve controlling the flow of fuel through said conduit having a plurality of external flow controlling surfaces thereon, and a plurality of
- 75 76. A charge forming device for internal combustion engines comprising a mixing chamber, fuel and air inlets therefor, a fuel reservoir, a fuel supply conduit connecting the fuel inlet and reservoir, a valve controlling the flow of fuel through said conduit having a plurality of external flow controlling surfaces thereon, and a plurality of
- 80 81. A charge forming device for internal combustion engines comprising a mixing chamber, fuel and air inlets therefor, a fuel reservoir, a fuel supply conduit connecting the fuel inlet and reservoir, a valve controlling the flow of fuel through said conduit having a plurality of external flow controlling surfaces thereon, and a plurality of
- 85 86. A charge forming device for internal combustion engines comprising a mixing chamber, fuel and air inlets therefor, a fuel reservoir, a fuel supply conduit connecting the fuel inlet and reservoir, a valve controlling the flow of fuel through said conduit having a plurality of external flow controlling surfaces thereon, and a plurality of
- 90 91. A charge forming device for internal combustion engines comprising a mixing chamber, fuel and air inlets therefor, a fuel reservoir, a fuel supply conduit connecting the fuel inlet and reservoir, a valve controlling the flow of fuel through said conduit having a plurality of external flow controlling surfaces thereon, and a plurality of
- 95 96. A charge forming device for internal combustion engines comprising a mixing chamber, fuel and air inlets therefor, a fuel reservoir, a fuel supply conduit connecting the fuel inlet and reservoir, a valve controlling the flow of fuel through said conduit having a plurality of external flow controlling surfaces thereon, and a plurality of

restrictions in said conduit adapted to cooperate with said surfaces.

35. A charge forming device for internal combustion engines comprising a mixing chamber, a fuel reservoir, an air inlet admitting air to said mixing chamber, low and high speed fuel inlets discharging fuel into said mixing chamber, separate fuel supply conduits connecting said inlets with the fuel reservoir, a suction operated valve in the conduit supplying fuel to the high speed fuel inlet for controlling the flow of fuel therethrough having a passage therethrough and a plurality of flow controlling surfaces thereon, and a plurality of restrictions in said conduit adapted to cooperate with said surfaces.

36. A charge forming device for internal combustion engines comprising a mixing chamber, a fuel reservoir, an air inlet admitting air to said mixing chamber, low and high speed fuel inlets discharging fuel into said mixing chamber, separate fuel supply conduits connecting said inlets with the fuel reservoir, a valve in the conduit supplying fuel to the high speed fuel inlet for controlling the flow of fuel therethrough having a plurality of flow controlling surfaces formed thereon, a plurality of restrictions of different size in said conduit and adapted to cooperate with said surfaces, said valve being so constructed that the flow controlling surfaces become effective successively to control the flow of fuel through said conduit.

37. A charge forming device for internal combustion engines comprising a mixing chamber, a fuel reservoir, an air inlet admitting air to said mixing chamber, low and high speed fuel inlets discharging fuel into said mixing chamber, separate fuel supply conduits connecting said inlets with the fuel reservoir, a suction operated valve in the conduit supplying fuel to the high speed fuel inlet for controlling the flow of fuel therethrough, having a plurality of flow controlling surfaces formed thereon, a plurality of restrictions of different size in said conduit and adapted to cooperate with said surfaces, said valve being so constructed that the flow controlling surfaces become effective successively to control the flow of fuel through said conduit.

38. A charge forming device for internal combustion engines comprising a mixing chamber, a fuel reservoir, an air inlet admitting air to said mixing chamber, a plurality of fuel inlets discharging fuel into said mixing chamber, separate conduits connecting said inlets with the fuel reservoir, a suction operated valve in one of said conduits for controlling the flow of fuel therethrough, said valve having a passage therethrough and a plurality of external flow controlling surfaces thereon, and a plurality of restrictions in said conduit adapted to cooperate with said surfaces.

39. A charge forming device for internal combustion engines comprising a mixing chamber, a fuel reservoir, an air inlet admitting air to said mixing chamber, a plurality of fuel inlets discharging fuel into said mixing chamber, separate conduits connecting said inlets with the fuel reservoir, a suction operated valve controlling the flow of fuel through one of said conduits having a plurality of external flow controlling surfaces formed thereon, a plurality of restrictions of different size in said conduit and adapted to cooperate with said surfaces, said valve being so constructed that the flow controlling surfaces become effective successively to control the flow of fuel through said conduit.

40. A charge forming device for internal combustion engines having a plurality of intake ports, a plurality of secondary mixing chambers communicating with said intake ports, a plurality of primary carburetors for supplying a primary fuel mixture to said secondary mixing chambers, fuel inlets, one of which discharges fuel into the mixing chamber of each primary carburetor, a fuel reservoir, a fuel conduit conveying fuel from said reservoir to all of said fuel inlets, a fuel valve for controlling the flow of fuel through said conduit, having a passage therethrough and a plurality of external flow controlling surfaces formed thereon, and a plurality of restrictions of different size in said conduit adapted to cooperate with said surfaces.

41. A charge forming device for internal combustion engines having a plurality of intake ports, a plurality of secondary mixing chambers communicating with said intake ports, a plurality of primary carburetors for supplying a primary fuel mixture to said secondary mixing chambers, high and low speed fuel inlets discharging fuel into the mixing chamber of each primary carburetor, separate fuel supply conduits, one of which supplies fuel to all of the high speed fuel inlets and the other of which supplies fuel to all of the low speed fuel inlets, a valve for controlling the flow of fuel through the conduit supplying the high speed fuel inlets and having a plurality of external flow controlling surfaces formed thereon and a passage therethrough, and a plurality of restrictions in the fuel conduit cooperating therewith.

42. A charge forming device for internal combustion engines having a plurality of intake ports, a plurality of secondary mixing chambers communicating with said intake ports, a plurality of primary carburetors for supplying a primary fuel mixture to said secondary mixing chambers, high and low speed fuel inlets discharging fuel into the mixing chamber of each primary carburetor, separate fuel supply conduits, one of which supplies fuel to all of the high speed fuel inlets and the other of which supplies fuel to all of the low speed fuel inlets, a valve for controlling the flow of fuel through the conduit supplying the high speed fuel inlets and having a plurality of external flow controlling surfaces formed thereon, and a plurality of restrictions of different size in the fuel conduit adapted to cooperate with said surfaces, said valve being so constructed that the flow controlling surfaces become effective successively to control the flow of fuel.

43. A charge forming device for internal combustion engines having a plurality of intake ports comprising an individual primary carburetor for supplying fuel mixture to each intake port, a fuel reservoir, a fuel duct for conveying fuel from said reservoir to all of said primary carburetors, a suction operated valve for controlling the flow of fuel through said duct having a plurality of external flow controlling surfaces formed thereon and restrictions in said duct adapted to cooperate with said surfaces, the valve being moved by suction so as to render the surfaces effective successively to control the flow of fuel.

44. A charge forming device for internal combustion engines having a plurality of intake ports, a plurality of secondary mixing chambers communicating with said intake ports, a plurality of primary carburetors for supplying a primary fuel mixture to said secondary mixing chambers, high and low speed fuel inlets discharging fuel into the mixing chamber of each primary carburetor,

separate fuel supply conduits, one of which supplies fuel to all of the high speed fuel inlets and the other of which supplies fuel to all of the low speed fuel inlets, a suction operated valve for controlling the flow of fuel through the conduit supplying the high speed fuel inlets and having a plurality of external flow controlling surfaces formed thereon, and a plurality of restrictions in the fuel conduit adapted to cooperate with said surfaces, the valve being moved by suction to render said flow controlling surfaces effective successively.

45. A charge forming device for internal combustion engines comprising a plurality of secondary mixing chambers, a plurality of primary mixing chambers adapted to deliver a primary mixture of air and fuel to said secondary mixing chambers, fuel and air inlets therefor, a fuel reservoir, a primary throttle controlling said primary mixing chambers, a well for supplying additional fuel to all of said primary mixing chambers, a plurality of outlet passages leading from the well to said mixing chambers, and a plurality of vent passages each of which communicates with one of said outlet passages between the well and the mixing chamber whereby equal distribution of fuel from said well to the various mixing chambers is secured, and a pump operated by the primary throttle for forcing fuel into the well.

30 46. A charge forming device for internal combustion engines comprising a fuel reservoir, a mixing chamber, a fuel inlet therefor, a suction operated valve controlling admission of air to said mixing chamber, a dash pot for resisting opening movements of said valve comprising a cylinder and a piston slidable therein, an auxiliary cylinder communicating with the dash pot cylinder, a piston in said auxiliary cylinder, a spring normally holding said last named piston in position to render the dash pot effective, said spring being adapted to yield to permit movement of the piston to a position where the dash pot is rendered ineffective when the suction on the valve is sufficient to overcome the pressure of said spring.

45 47. A charge forming device for internal combustion engines comprising a fuel reservoir, a secondary mixing chamber, a primary carburetor adapted to deliver a primary mixture of fuel and air to said secondary mixing chamber, means for supplying fuel and air to the primary carburetor, a secondary air passage supplying air to said primary carburetor, a secondary air valve admitting air to said secondary mixing chamber, a dash pot for resisting opening movements of said secondary air valve comprising a cylinder having a piston slidable therein and connected to the secondary air valve for movement therewith, an auxiliary cylinder communicating with the dash pot cylinder, a piston in said auxiliary cylinder, a port in said auxiliary cylinder communicating with the fuel reservoir and adapted to control the resisting effect of the dash pot, means normally holding the last named piston in position to close the port to render the dash pot effective, said means being rendered ineffective by a predetermined degree of suction on the air valve.

48. A charge forming device for internal combustion engines comprising a fuel reservoir, a secondary mixing chamber, a primary carburetor adapted to deliver a primary mixture of fuel and air to said secondary mixing chamber, means for supplying fuel and air to the primary carburetor, a secondary air passage supplying air to said primary carburetor, a secondary air valve admitting air to said secondary mixing chamber, a dash pot

for resisting opening movements of said secondary air valve comprising a cylinder having a piston slidable therein and connected to the secondary air valve for movement therewith, an auxiliary cylinder communicating with the dash pot cylinder, a piston in said auxiliary cylinder, resilient means normally holding the piston in said auxiliary cylinder in position to close the port and render the dash pot effective to resist normal opening movements of the air valve, said resilient means being adapted to yield to permit movement of the last named piston to position to open the port and render the dash pot ineffective when the suction on the air valve is sufficient to overcome the pressure of said resilient means on the piston.

49. A charge forming device for internal combustion engines comprising a fuel reservoir, a secondary mixing chamber, a primary carburetor adapted to deliver a primary mixture of air and fuel to said secondary mixing chamber, means for supplying fuel and air to said primary carburetor, a primary throttle controlling the flow from the primary carburetor, a secondary air passage supplying air to the secondary mixing chamber, a secondary air throttle therein, an additional suction operated valve in said secondary air passage, a dash pot for resisting opening movements of said suction operated valve comprising a cylinder having a piston slidable therein and connected to said suction operated valve for movement therewith, an auxiliary cylinder communicating with the dash pot cylinder, a piston in said auxiliary cylinder, a port in said auxiliary cylinder communicating with the fuel reservoir and adapted to regulate the admission of fuel from the reservoir to control the resisting effect of the dash pot, and means normally holding the last named piston in position to close the port to render the dash pot effective.

50. A charge forming device for internal combustion engines comprising a fuel reservoir, a mixing chamber, a fuel inlet therefor, a suction operated valve controlling admission of air to said mixing chamber, a dash pot for resisting opening movements of said valve comprising a cylinder and a piston slidable therein, an auxiliary cylinder communicating with the dash pot cylinder, a piston in said auxiliary cylinder, a port in said auxiliary cylinder communicating with the fuel reservoir, an annular projecting flange on the interior of said auxiliary cylinder surrounding said port and forming a seat for said last named piston when the piston is held against said seat whereby the pressure of the fuel reservoir is effective on a relatively small part of the piston head, means normally holding the piston in contact with said flange but constructed to permit the piston to be moved away from said flange when the suction on the air valve is relatively great so that the pressure of the fuel reservoir is communicated to the entire surface of the piston head in order to reduce the resisting effect of the dash pot.

51. A charge forming device for internal combustion engines comprising a mixing chamber, means for supplying fuel and air thereto, a throttle controlling the flow of mixture therefrom, an operating shaft for the throttle, a passage supplying additional air, a valve in said passage, a fuel pump for supplying additional fuel during the acceleration period, and cams operated by the throttle and adapted to operate the air valve and the fuel pump.

52. A charge forming device for internal com-

bustion engines comprising a mixing chamber, means for supplying fuel and air thereto, a throttle controlling the flow of mixture therefrom, an operating shaft for the throttle, a passage supplying additional air, a valve in said passage, a fuel pump for supplying additional fuel during the acceleration period, a fuel valve adapted to control the supply of additional fuel during relatively high speed operation, and a plurality of 10 cams operable by the throttle and adapted to operate the air valve, the pump and the fuel valve.

53. A charge forming device for internal combustion engines comprising a secondary mixing 15 chamber, a primary carburetor adapted to deliver a primary mixture of fuel and air thereto, means for supplying fuel and air to the primary carburetor, a primary throttle controlling the flow therefrom, a secondary air passage adapted 20 to supply air to the secondary mixing chamber, a secondary air throttle therein, a cam operated by said primary throttle for operating the air throt-

tle after a predetermined movement of the primary throttle, a fuel pump for supplying additional fuel during the acceleration period, a fuel valve for controlling the admission of additional fuel at relatively high speeds and other cams operated by the primary throttle and adapted to operate the fuel pump and the fuel valve. 5

54. A charge forming device for internal combustion engines comprising a mixing chamber, an air inlet therefor, a plurality of fuel inlets discharging fuel into the mixing chamber, a throttle 10 controlling the flow of fuel mixture from said mixing chamber, a plurality of fuel passageways supplying fuel to said fuel inlets, throttle operated means for rendering one of said fuel passages effective, and fixed and variable flow controlling restrictions in said last named passageway. 15
